UNITED STATES PATENT OFFICE.

RICHARD M. KLEIN, OF NEW YORK, N. Y., ASSIGNOR TO F. A. D. ANDREA, INC., OF NEW YORK, N. Y., A CORPORATION OF NEW YORK.

ADJUSTABLE CONDENSER.

Application filed November 1, 1924. Serial No. 747,204.

This invention relates in general to electric systems or circuit arrangements of wave signaling systems such as those described in U. S. Letters Patent to Hazeltine Nos. 5 1,450,080 and 1,489,228, wherein inherent or natural capacity coupling between parts or portions thereof is neutralized by the proper adjustment of a condenser of extremely small capacity; and has for its object the 10 provision of a condenser of improved design particularly applicable to neutralizing undesirable capacity coupling in radio receivers utilizing various types of vacuum tubes of different characteristics.

15 In order to change vacuum tubes of one type to vacuum tubes of another type in radio receiving apparatus which employs neutralization of capacity coupling, it has heretofore been necessary to repeat the permanent adjustment of the neutralizing condensers by means of the somewhat cumbersome balancing process required at the time when the receiver is first assembled.

20 The present invention provides a neutralizing condenser which may be permanently adjusted initially to effect the neutralization of the inherent inter-electrode capacity of various types of tubes, any one of which may thereafter be used in the same receiver with the mere requirement of setting the neutralizing condenser to the permanent position indicated thereon as being the proper setting predetermined for a given type of tube.

25 A better understanding of the present invention and an additional appreciation of its advantages may be had from a consideration of the following description of a preferred embodiment as illustrated in the accompanying drawings, in which

Fig. 1 represents a plan view of an adjustable condenser incorporating this invention;

Fig. 2 is a vertical section taken through line 2-2 of Fig. 1; and

Fig. 3 shows a circuit diagram of a capacity-neutralized tuned radio-frequency amplifier to which this invention is especially applicable.

50 Referring now to Figs. 1 and 2 of the drawing: The adjustable condenser is mounted upon an insulating base 1 and may comprise a tubular metallic electrode 2 surrounding a tubular dielectric 3, which may 55 be of any suitable dielectric material such

as glass or hard rubber, and one, or preferably two, inside rod-like electrodes 4 and 5. It will be observed that the electrode 4 is not fixed as is electrode 5, but it is movable and may be adjusted axially with reference to electrode 2 in order to vary the dielectric surface included between electrodes 2 and 4. As represented in the drawing, electrode 5 is preferably stationary and is secured by a screw to connecting lug 6. 60 Electrodes 4 and 5 are conveniently formed from No. 14 B. & S. gauge copper wire, electrode 4 being longer and having a manipulating handle 7 on its outside end. This handle is so formed as to serve as an indicator 8, which may be set at any desired indicated position 9, such as "D" or "S" marked on base 1. The letter "D" in this instance represents a setting of the condenser which will serve to neutralize the inherent 65 interelectrode capacity coupling of a so-called "dry cell tube" in accordance with the disclosure of the aforementioned Hazeltine patents; and, likewise, the letter "S" represents the proper setting to neutralize the inherent inter-electrode capacity coupling of a so-called "storage battery tube". If the capacity of the neutralizing condenser is so chosen relatively to the number of 70 turns N_1 and N_2 of coils L_1 and L_2 , Fig. 3, 75 respectively, that the ratio of the interelectrode capacity to be neutralized to the capacity of the neutralizing condenser is

75 equal to $\frac{N_2}{N_1}$, then the magneto-motive force 80 of L_2 will equal and cancel that of L_1 , provided the coils have the proper relative polarity, viz, the terminals connected together must be of unlike polarity. No voltage will 85 then be induced in either coil, and, therefore, 90 no variation can occur in the grid potential due to the variation in the plate potential, assuming the resistances of the coils negligible in comparison to their reactances; hence the undesirable effects of capacity 95 coupling will have been eliminated. A full and complete discussion of this method for neutralizing capacity coupling will be found in the Hazeltine patents referred to. It is, 100 of course, sometimes desirable to mark these 105 positions in other ways, such as by indicating the values of the capacities directly, or by using an arbitrary scale. Fig. 1, illustrating the preferred embodiment, shows the 110 indications marked upon the base of the

- condenser, but it is frequently convenient to place marks upon the condenser itself, particularly when space does not permit of a scale or other indicating means. In order 5 that any desired adjustment of the condenser may be maintained and an accurate setting held indefinitely, notches 10 have been provided in electrode 4, into which engages projection 11 of a spring contact member 10. A screw having a slotted head 13 may be provided to support the electrode 4 under the pressure of spring 12 so that the electrode may slide longitudinally through the slot. Spring 12 is secured to the base 1 by 15 a screw 20 and terminates in a connecting lug 14, to which a connecting wire may be attached. Ordinarily the condenser is connected into its circuit by means of lugs 6 and 14, this connection resulting actually 20 in two capacities being connected in series, the first capacity existing between electrodes 5 and 2, and the second capacity between electrodes 2 and 4. The resultant capacity 25 of these two in series may be varied by sliding intermediate electrode 2 so as to include more or less dielectric surface between it and the two inside electrodes, and also, as above described, by sliding electrode 4 in or out of the dielectric tube 3. It is preferable, practically, to set the intermediate electrode 2 at the time when the condenser is first calibrated and then to lock that electrode against inadvertent movement by 30 means of clamp 17 and screw 16. Lug 15 is provided to make contact with electrode 2 in case the connection through lug 6 provides too small a resultant capacity. The dielectric tube 3 is secured against movement by means of a clamp 19 and screw 18. 40 At the present time there are on the American market vacuum tubes, for reception purposes, of three general types ranging in grid-plate capacities from about 15 micro-microfarads to about 25 micro-microfarads. 45 Two of these types are adapted to be supplied with filament heating current derived from dry cells, and the other type is adapted to draw current from storage batteries. It is thus possible for the owner of a receiver 50 incorporating the invention described herein to change from "dry cell tubes" to "storage battery tubes" with the sole requirement of moving the setting of the neutralizing con-
- densers from position "D" to "S" with the assurance that the receiver will then be correctly neutralized. Since the initial calibration and permanent setting of the neutralizing condensers for the proper and efficient operation of radio receivers embodying the Hazeltine principle of neutralization of capacity coupling involves the use of an elaborate testing apparatus and skill not to be expected of the general public, it will be readily appreciated that the present invention provides an extremely simple means for 60 making feasible the interchange of vacuum tubes of certain definite characteristics in the type of receiver to which this invention is peculiarly adapted.
- The wiring diagram of such a receiver is 70 shown in Fig. 3, which represents a radio receiver embodying two stages of tuned radio-frequency amplification in which the grid-plate coupling capacity of the vacuum tubes A and A₁ is neutralized by neutralizing condensers C_n and C'_n in cooperation with a winding of interstage coupling transformers T₁ and T₂ respectively. A detector tube A₂ is shown connected in the customary manner to the output of transformer T₂, and includes 80 in its plate circuit telephone receivers R. In order to simplify the diagram, the usual audio frequency amplifiers have been omitted from Fig. 3, since it is here desired to illustrate the application of this invention to a 85 radio-frequency amplifying system. The present invention is obviously applicable to other uses, however, such as the neutralization of capacity coupling between coils, between portions of various circuits, or between 90 electrodes of vacuum tubes utilized for various other purposes.
- I claim:
- An electrostatic condenser comprising two rod-like electrodes, one of said electrodes being movable toward and away from the other for varying the capacity of the condenser, said movable electrode being provided with a plurality of spaced stops and means operable to engage said stops individually, said 95 means and said stops being operable jointly to maintain the setting of the condenser at any one of a plurality of predetermined capacity values.
- In testimony whereof I affix my signature.
- RICHARD M. KLEIN.
